UNITED STATES PATENT OFFICE

151,218

DESIGN FOR A CHILD'S DESK

Paul P. Cameron, Flint, Mich., assignor to Parker Products Company, Flint, Mich., a corporation of Michigan

Application March 10, 1947, Serial No. 137,492

Term of patent 3½ years

(Cl. D33—7)

To all whom it may concern:

Be it known that I, Paul P. Cameron, a citizen of the United States, residing at Flint, in the county of Genesee and State of Michigan, have invented a new, original, and ornamental Design for Child's Desk, of which the following is a specification, reference being had to the accompanying drawing, forming part thereof.

Fig. 1 is an angular perspective view of the child's desk, showing the new design, looking toward the front and one side thereof.

Fig. 2 is an angular perspective view of the same, looking toward the back and opposite side thereof.

I claim:

The ornamental design for a child's desk, substantially as shown.

PAUL P. CAMERON.
